UNITED STATES PATENT OFFICE

EDWARD C. KLINE, OF STREATOR, ILLINOIS

HEATING APPARATUS

Application filed June 28, 1926. Serial No. 119,101.

My invention belongs to that general class of devices known as heating apparatus, and more particularly relates to an improved hot water heater, steam boiler or the like for use wherever found applicable. My invention has among its objects the production of a device of the kind described that is simple, convenient, durable, compact and efficient. It has particularly as an object the production of a device that will not only be rapid and sensitive in operation, but will likewise be particularly economical in use as well as inexpensive in construction. Many other objects and advantages of the construction herein shown and described will be obvious to those skilled in the art from the disclosure herein given.

To this end my invention consists in the novel construction, arrangement and combination of parts herein shown and described, and more particularly pointed out in the claim.

In the drawings, wherein like reference characters indicate like or corresponding parts:

Fig. 1 is a vertical sectional view through a heater embodying my invention;

Fig. 2 is a sectional view taken substantially on line 2—2 of Fig. 1, the upper brick work removed;

Fig. 3 is a section taken on line 3—3 of Fig. 1;

Fig. 4 is a section taken on line 4—4 of Fig. 1;

Fig. 5 is a section taken on line 5—5 of Fig. 1;

Fig. 6 is a section taken on line 6—6 of Fig. 4;

Fig. 7 is a sectional view similar to Fig. 1 showing another form of the invention;

Fig. 8 is a section taken on line 8—8 of Fig. 7;

Fig. 9 is a sectional view similar to Fig. 3 illustrating a modified arrangement of feed and return pipes; and

Fig. 10 is a sectional view taken substantially on line 10—10 of Fig. 9.

Referring for the present to Figs. 1 to 6, inclusive, wherein I have shown a preferred form of the invention embodied in a heater,

the reference character 15 designates generally the housing or setting for the heater, the setting 15 being formed of any suitable material, but being preferably constructed from bricks or other refractory material. In this instance the setting 15 comprises front and rear walls 16 and 17, respectively, side walls 18 and a top wall 19. Disposed in the lower part of the setting 15 is a grate 20, or the equivalent, the grate being so positioned that the hot gases of combustion may flow upwardly through the setting to a flue 22 opening into the rear wall 17. The flue 22 is preferably provided with a damper 23 and a check draft regulator 24. Access may be had to an ash pit 26 below the grate 20 through a door 27 suitably mounted upon the front wall 16, a similar door 28 being provided in the front wall 16 to permit the grate 20 to be charged with coal or the equivalent. The purpose of a plurality of relatively large apertures 31 formed in the front wall 16 will presently be described. It will be noted that these apertures 31 are normally closed by covers or doors 33 which may be movably secured to the front wall by any suitable means.

Disposed in the setting 15 and positioned above the grate 20 are a plurality of substantially flat hollow members which are identified by the reference characters 35, 36, 37, 38, 39, 40 and 41, the hollow members being disposed one above the other in spaced relation. It will be noted that the lowermost hollow member is designated by the reference character 35 and that the uppermost hollow member is designated by the reference character 41. While the hollow members 35 to 41, inclusive, may be of any suitable shape and may be formed from any suitable material, I preferably form them from cast iron and give them a substantially rectangular shape. As best shown in Fig. 2, the setting 15 is substantially rectangular in cross section and as best shown in Fig. 3 the width of each of the hollow members 35 to 41, inclusive, is substantially equal to the distance between the side walls 18 of the housing. And as shown in Fig. 1, the hollow members 35 to 41, inclusive, are preferably arranged in staggered relation, the front ends of the hollow mem-

bers 35, 37, 39 and 41 being positioned against the front wall 16 and the rear ends of the hollow members 36, 38 and 40 being positioned against the rear wall 17. It is readily understood that the hollow members 35 to 41, inclusive, serve as baffles so that the hot gases of combustion must flow through a circuitous path as they pass from the grate 20 to the flue 22. The flow of the hot gases is indicated by arrows in Fig. 1.

The hollow members 35 to 41, inclusive, may be supported within the setting 15 by any suitable means and in any suitable manner, but I prefer to support them by having the marginal edges thereof rest upon shoulders 43 formed in the walls of the setting. To prevent warping of the hollow members and also to reinforce them against the action of pressures obtaining therein, I preferably provide a plurality of integral tubular members 45 in each hollow member, the tubular members 45 preferably extending from the bottom wall of each hollow member to the top thereof. For reasons hereinafter set forth, I preferably close the apertures so formed in the hollow members 35 to 41, inclusive, by buttons 46 or the equivalent, each button 46 preferably comprising a shank 47 adapted to project into one of the apertures formed in the hollow member and a head 48 for preventing it from falling therethrough.

The hollow members 35 to 41, inclusive, preferably communicate with each other through a plurality of nipples 50, or the equivalent, which are provided with tapered ends 51 adapted to seat in tapered apertures 52 formed in the walls of the hollow members (see Fig. 4). The nipples 50 are so positioned that tie rods 54 may extend therethrough, the tie rods 54 preferably extending from above the top wall of the hollow member 41 into the bottom wall of the hollow member 35 (see Fig. 5). The lower ends of the tie rods 54 are preferably screw-threaded into tapped holes 56 formed in the bottom wall of the hollow member 35 and nuts 57 are preferably screw-threaded upon the upper ends of the tie rods in such manner that the nuts may be manipulated to tension the tie rods. Obviously, when the nuts 57 are tightened, the hollow members 35 to 41, inclusive, and the nipples 50 are rigidly secured to each other in such manner that they substantially form a unitary structure. I prefer to provide packing 59 of sheet brass or any other suitable material between the nuts 57 and the upper surface of the hollow member 41 to prevent leaks at these points.

Referring now to Fig. 3, wherein I have shown a return pipe 60, it will be noted that the return pipe 60 communicates with the hollow member 35 through a pipe section 61, the return pipe 60 being operatively connected to the pipe section 61 by an elbow 62. At 65 I have shown a feed water pipe which may be

connected to any suitable supply (not shown) of water. Communication between the feed pipe 65 and the pipe section 61 is controlled by a valve 66.

The contents of the hollow members 35 to 41, inclusive, are preferably discharged therefrom through a plurality of pipes 68 which may be operatively connected to a plurality of radiators (not shown) or the equivalent, the return pipes of the radiators being operatively connected to the return pipe 60 by other piping (not shown).

The heater illustrated in Figs. 1 to 6, inclusive, is particularly adapted to be incorporated in a hot water heating system and the operation thereof is substantially as follows: Assuming that the discharge pipes 68 and the return pipe 60 have been operatively connected to a plurality of radiators and assuming that there is a sufficient supply of water in the system, the valve 66 being closed, the hot gases of combustion will pass between the hollow members 35 to 41, inclusive, in the manner indicated by the arrows in Fig. 1 and the water within the hollow members will be heated. Obviously, the heated water will flow upward through the pipes 68 to the radiators (not shown) and then return to the hollow members through the return pipe 60. It is readily understood that the supply of water in the system may be replenished from time to time by opening the valve 66, which then permits water to flow from the pipe 65 into the system.

The thickness of the hollow members 35 to 41, inclusive, may be as desired, but in the preferred embodiment of the invention I prefer to make the uppermost and lowermost hollow members of greater thickness than the intermediate hollow members as the return and discharge pipes are connected to the lowermost and uppermost hollow members, respectively. While I have shown the hollow members spaced equidistantly from each other, it is to be understood that I am not limited to this arrangement as in some instances I prefer to vary the spacing.

The heater shown in Figs. 1 to 6, inclusive, is exceedingly efficient as the water being heated is being distributed in relatively thin sheets in the hollow members so that there is an efficient exchange of heat between the hot gases of combustion and the water. The heater may be brought into effective operation in an extremely short period of time. This is, of course, mainly due to the fact that the water passes in relatively thin sheets through the heater. A feature of the invention is that deposits of soot upon the hollow members may be removed through the aforementioned apertures 31 provided in the front wall 16, thus insuring that the efficiency of the heater will be maintained at all times.

Referring to Figs. 7 and 8 I have shown another form of the invention embodied in a

heater particularly adapted to be incorporated in a steam heating system. The heater shown in Figs. 7 and 8 preferably comprises a housing or setting 70 having front and rear walls 71 and 72, respectively, side walls 73 and a top wall 74. The setting 70 may be formed of any suitable material, but preferably comprises brick or any other refractory material. A grate 75 or the equivalent 5 is preferably positioned in the lower part of the setting 70, the hot gases of combustion rising from the grate being discharged from the setting through a flue 76 communicating with the interior of the setting through the rear wall 72. Fuel may be supplied to the 10 grate 75 through a door 78 hinged to the front wall 71 and ashes may be removed from the setting through a door 79 also hinged to the front wall. A plurality of relatively 15 large apertures 80 are preferably provided in the front wall 71 for substantially the same purpose that the apertures 31 are provided in the aforementioned front wall 16, the apertures 80 being normally closed by covers or 20 doors 82. Hollow members resembling the aforementioned hollow members 35 to 41, inclusive, and designated by the reference characters 84, 85, 86, 87, 88, 89 and 90 are mounted within the setting 70 in spaced relation and 25 are preferably supported upon shoulders 92 formed upon the interior surfaces of the walls thereof. Each of the hollow members 84 to 90, inclusive, is substantially equal in width to the distance between the side walls 30 73 so that the hot gases of combustion will not pass around the side edges thereof. As best shown in Fig. 7, the hollow members 84 to 90, inclusive, are arranged in staggered relation, the front edges of the hollow members 84, 86, 40 88 and 90 abutting the front wall 71 and the rear edges of the hollow members 85, 87 and 89 abutting the rear wall 72. A pipe 95 which communicates with the lowermost hollow member 84 is preferably employed as the 45 return pipe of a steam heating system, the pipe 95 being connected to the radiators (not shown) thereof. Steam may be discharged from the uppermost hollow member 90 through one or more discharge pipes 97 which 50 are also connected to the radiators (not shown) of the steam heating system. The hollow members 84 to 90, inclusive, preferably communicate with each other through a plurality of nipples 98 which are substantially 55 identical to the aforementioned nipples 50. Extending through the hollow members and the nipples 98 are tie rods 100 screw-threaded into the bottom wall of the hollow member 84 and provided with nuts 102 which may be 60 manipulated to secure the hollow members and the nipples 98 to form the hollow members 84 to 90, inclusive, and the nipples 98 into a substantially rigid structure. It will be noted that this construction is similar to 65 the construction shown in Figs. 1 to 6, includ- 70 75 80 85 90 95 100 105 110 115 120 125 130

sive. The lowermost hollow member 84 is preferably somewhat thicker than the hollow members 85 to 90, inclusive, as it receives the water from the return pipe 95. The uppermost hollow member 90 is preferably several times thicker than any one of the hollow members 84 to 89, inclusive, as it serves as a steam chamber. As illustrated, the system preferably contains sufficient water to substantially fill the hollow members 84 to 89, inclusive, and to partially fill the hollow member 90.

The operation of the heater shown in Figs. 7 and 8 resembles the operation of the heater shown in Figs. 1 to 6, inclusive, and is substantially as follows: Assuming that a fire is burning upon the grate 75, the hot gases of combustion pass between the hollow members 84 to 90, inclusive, in the manner indicated by the arrows shown in Fig. 7. Steam is quickly generated in the hollow members and passes to the steam chamber or hollow member 90 through the nipples 98, after which the steam passes to the radiators (not shown) of the steam heating system through the pipes 97. When the steam condenses in the radiators, it returns to the hollow member 84 through the return pipe 95.

It will be noted that the hollow members 84 to 90, inclusive, are substantially flat and that the hollow members 84 to 89, inclusive, are relatively thin so that there is an efficient exchange of heat between the hot gases of combustion and the water contained in the hollow members. The hollow members 84 to 90, inclusive, are preferably reinforced by integral tubular members 105 which are substantially identical in construction with the aforementioned tubular members 45. The apertures thus formed in the hollow members 84 to 90, inclusive, are preferably closed by buttons 106 substantially identical with the aforementioned buttons 46.

Referring now to Figs. 9 and 10, wherein I have shown still another form of the invention embodied in a heater, the reference character 110 designates a setting constructed from brick or any other suitable material and provided with side walls 111, a top wall 112 and front and rear walls 113 and 114, respectively. The setting 110 is preferably provided with a grate 115, or the equivalent, and a plurality of hollow members 117, 118, 119, 120, 121, 122 and 123 are arranged above the grate, the hollow members 117 to 123, inclusive, being substantially identical in construction with the aforementioned hollow members 84 to 90, inclusive. Each of the hollow members 117 to 123, inclusive, is substantially equal in width to the distance between the side walls 111 and the hollow members are preferably arranged in staggered relation in substantially the same manner as the hollow members 35 to 41, inclusive. The hollow members 117 to 123 communicate with 130

each other through nipples 125, rods 126 extending through the nipples being adapted to secure the hollow members and the nipples to each other to form a substantially unitary structure. Connected to each of the hollow members 117 to 123, inclusive, are return pipes 127 which connect the hollow members with a main 128. Also communicating with each of the hollow members 117 to 123, 10 inclusive, are discharge pipes 129 which connect the hollow members with a main 130. The mains 128 and 130 are adapted to connect a plurality of radiators or the equivalent to the heater. Water may be introduced to 15 the heating system through a pipe 133 which communicates with any suitable supply (not shown) of water. The flow of water through the pipe 133 to the main 128 is preferably controlled by a valve 134.

20 The operation of the heater shown in Figs. 9 and 10 is substantially the same as the heater shown in Figs. 1 to 6, inclusive, with the exception that the heated water does not necessarily travel upwardly through the several 25 hollow members before passing to the radiators of the system. Obviously, the water may be heated in a minimum of time as the water may flow into any one of the hollow members from the return pipe and then, when 30 heated, pass directly into the discharge pipe. In the embodiment of the invention shown in Figs. 1 to 6, inclusive, the water enters the lowermost hollow member and travels upward through the other hollow members to 35 the discharge pipe.

In boilers embodying my invention the hot gases must travel back and forth between the sheets of water in the hollow members and as 40 the hollow members each have an area nearly equaling the cross sectional area of the boiler, there is a maximum heating surface therein.

Boilers embodying my invention are particularly adaptable for gas heaters, especially 45 of a small type such as are used for heating bathrooms and other small enclosures.

Having thus described my invention, it is 50 obvious that various immaterial modifications may be made in the same without departing from the spirit of my invention; hence I do not wish to be understood as limiting myself to the exact form, construction, arrangement and combination of parts herein shown and described or uses mentioned.

55 What I claim as new and desire to secure by Letters Patent is:

In a boiler for heating dwellings or the like, comprising front, rear and side walls, a plurality of vertically spaced substantially flat 60 hollow members arranged as baffles within said walls, integral tubular reinforcing members extending through each of said hollow members, closures for said reinforcing members, nipples disposed between said hollow members and beveled therein, tie rods extend-

ing through the nipples and hollow members for securing said members in fixed relation to each other and to the boiler casing, a fluid inlet pipe communicating with the lowermost of said hollow members, and a discharge pipe communicating with the uppermost hollow member.

In testimony whereof, I have hereunto signed my name.

EDWARD C. KLINE.
